UNITED STATES PATENT OFFICE.

JAMES C. OLLARD, OF CLEVELAND, OHIO.

DOOR BUFFER.

Application filed October 27, 1920, Serial No. 419,957. Renewed January 6, 1923. Serial No. 489,050.

To all whom it may concern:

Be it known that I, JAMES C. OLLARD, a citizen of the United States, residing at Cleveland, in the county of Cuyahoga and 5 State of Ohio, have invented new and useful Improvements in Door Buffers, of which the following is a specification.

The invention relates to a combined door stop and antirattle door buffer and dovetail for automobiles.

The object of the present invention is to provide a simple, practical and efficient combined door stop, antirattle automobile door buffer and dovetail of strong, durable 15 and comparatively inexpensive construction and adapted to be employed on door frames where the face or edge of the door frame is made plain or stopless, that is without a rabbet to receive the free edge or portion 20 of the automobile door.

It is also an object of the invention to provide an automobile door buffer of this character equipped with anchoring lugs adapted to be driven into the wood of the 25 door frame and capable of maintaining the buffer alone in proper position and of relieving the attaching screws of bearing strain.

Another object of the invention is to provide a combined door stop and antirattle door buffer and dovetail composed of pin and socket interfitting elements or members adapted to prevent upward and downward movement of an automobile door and 35 thereby stop any rattling of the same and at the same time provide means which will be yieldable and constantly forced against the door so as to prevent any inward and outward movement and resulting rattle.

With these and other objects in view the invention consists in the novel construction, combination and arrangement of parts hereinafter fully described, illustrated in the accompanying drawing, and pointed out in the 45 claims hereto appended, it being understood that various changes in the form, proportion and minor details of construction, within the scope of the claims, may be resorted to without departing from the spirit or sacrificing 50 any of the advantages of the invention:

In the drawings in which like characters of reference designate corresponding parts in the several figures;

Figure 1 is a vertical sectional view of a 55 combined door stop and antirattle door buf-

fer constructed in accordance with this invention and shown applied to a portion of an automobile.

Figure 2 is a horizontal sectional view of the same.

Figure 3 is an elevation of the buffer showing the same applied to the door frame.

Figure 4 is a similar view of a portion of the door showing the coacting buffer engaging device.

Figure 5 is a rear elevation of the buffer.

Figure 6 is a front elevation of the same.

Figures 7 and 8 are detail views of the interlocking portions of the casing of the buffer.

Figure 9 is a detail view illustrating the manner of bowing the tongue or flange portion of the casing of the buffer to enable it to interlock with the coacting terminal portion of the material of the casing.

Figure 10 is a front elevation of a buffer illustrating another form of the invention.

Figure 11 is a plan view of the same.

Figure 12 is a horizontal sectional view of the same.

Figure 13 is a vertical sectional view of the buffer shown in Figures 10 to 12 inclusive.

Figure 14 is a detail perspective view of a buffer casing illustrating another form of the invention.

Figure 15 is a horizontal sectional view showing the form of buffer illustrated in Figure 14, applied to a door frame and casing having rabbeted portions to form a door stop.

Figure 16 is a side elevation of a buffer illustrating another form of the invention.

Figure 17 is a front elevation of the same.

Figure 18 is a horizontal sectional view of the buffer.

Figure 19 is a vertical sectional view through the casing portion of the same.

Referring particularly to the form of the invention illustrated in Figures 1 to 9 inclusive of the drawings, the buffer which comprises a casing 1, a door engaging member 2 and a coiled spring 3 cooperates with a buffer engaging spring 4 which is secured to and carried by the door 5 of an automobile and which is adapted to prevent vertical vibration of the door and the rattling which ordinarily results from such vertical movement.

The spring 4 is approximately U-shaped and is secured within a recess 6 of

the door at the free edge thereof by means of a metallic strap 7 which is angularly bent as shown to fit the recessed portion of the door and which is secured to the same 5 at the terminals of the strap 7 by suitable fastening devices 8. The mounting of the buffer engaging spring in this manner prevents the piercing of the spring by screws or other fastening devices and thereby 10 avoids the weakening of the spring and increases the strength and durability of the same. The U-shaped buffer engaging spring has its terminal portions 9 curved or bowed as shown to provide a slightly flaring mouth or entrance and to present inner rounded or convex faces to the top and bottom of the buffer casing. This enables the buffer engaging spring to grip the casing of the buffer and at the same time permits 15 the casing to readily enter between the jaws or engaging side portions of the spring. 20

The casing 1 of the buffer which is formed from a single piece of sheet metal is bent to form an inner or front wall 11 and an outer 25 or rear wall 12, a connecting side wall 13 and top and bottom walls 14 and an inner side wall 15. The sheet metal is angularly bent at the sides and top of the connecting wall 13 and the front wall 11 is provided 30 with small projections 16 having recesses 17 at the inner edges to receive a projecting tongue or flange 18 of the inner side wall 15. The tongue or flange 18 is also provided at opposite sides with recesses or 35 notches 19 which engage or interlock with the recesses or notches 17 of the front wall 11 and the tongue or extension 18 of the inner side wall is bowed or bent as indicated in Figure 9 of the drawing to enable it to 40 readily pass through the space between the lugs or projections 16 and interlock with the notches or recesses 17. After the tongue or extension 18 has been placed in position it is straightened or flattened out to re- 45 move the bow or bend and the notched or recessed portions are thereby firmly interlocked with each other. The tongue or extension 18 is provided with a perforation to form an attaching ear or flange 18^a and the 50 top and bottom walls 14 are also provided with integral attaching ears or flanges 20, each having an integral right angle anchoring lug 20^a located at the front edge at opposite sides of the central ear 18^a and adapt- 55 ed to be embedded in the wood.

The front wall 11 is provided with a circular opening 21 to receive the door engaging member 2 which is in the form of a tapered hollow cap. The hollow cap is provided at the inner end with a stop flange 22 and the spring which has one end fitted within the door engaging member is engaged at the other end by a protuberance 23 formed by an indentation in the outer side 60 wall 12, but any other suitable form of pro-

tuberance may of course be employed and the inner side wall which fits against the door frame 24 is preferably provided with an opening 25 to afford ready access to the spring and to permit the same and the door 70 engaging member to be assembled after the casing has been completed. The door engaging member is forced inwardly and the spring is placed under compression by the closing of the door and the said member 75 and spring will hold the door against inward and outward movement and prevent rattling ordinarily resulting from such movements of the door.

In attaching the buffer casing to the door 80 frame the spaced tapering projecting anchoring lugs 20^a are driven into the door frame and the screws or other fastening devices are applied to the projecting ears. The tapering lugs will always maintain the 85 buffer in proper position on the door frame and will relieve the attaching screws of shearing strain. In Figures 10 to 13 inclusive of the drawings, is illustrated another 90 form of buffer in which the casing 26 is open at the inner side, the inner side wall of the casing heretofore described being omitted. The laterally extending ears 27 are provided with projecting right angle anchoring lugs 28 and the ear 29 is located 95 between the lugs. The central lug 29 is formed integral with the front wall and the spaced tapering anchoring lugs are formed integral with the top and bottom walls of the casing. The lugs are adapted to be 100 driven into a door frame and perform the function of the lugs heretofore explained. The buffer casing 26 is also provided at the top and bottom with ears 27.

In Figure 14 is illustrated a simpler form 105 of buffer casing 31 designed for use on a door frame 32 having a rabbet 33 to form a stock for a correspondingly rabbed door 34 as illustrated in Figure 15 of the drawings. The casing 31 is approximately U-shaped in horizontal section and is composed of spaced walls or portions 35 and 36 and a connecting portion which is provided with terminal attaching ears 37. The front wall or portion 35 is provided with 110 lugs 38 which are embedded in the door frame as clearly shown in Figure 15 of the drawings. The door frame as indicated in Figure 15 of the drawings is recessed 115 to receive the buffer.

In Figures 16 to 19 inclusive of the drawings, is illustrated another embodiment of the invention in which the side wall or attaching member 39 and the casing 40 have the spring 41 and the door engaging member 42 constructed from a single piece of sheet metal which is bent to form the combined inner or rear wall and attaching plate 39 and the front, side and rear walls of the casing 40. The front wall of the casing 40 120

is provided with an opening through which projects the door engaging member and which is provided with an integral extension 43 forming the top wall of the casing.

5 The casing is open at the bottom wall to permit the ready assembling of the spring and the door engaging member.

The sheet metal employed in the construction of the various forms of the invention 10 may be sheet steel or any other suitable material and the buffer illustrated in Figures 16 to 19 inclusive of the drawings is designed to cooperate with the approximate spring herebefore described to provide a 15 combined door stop and antirattle door buffer for automobiles. The engagement of the spring and the buffer provide an interlocking connection or device, the socket member being formed by the approximately 20 U-shaped spring and the buffer constituting the interfitting or pin member of the device. The attaching member formed by the rear wall or side plate 39 is provided with upper and lower ears having apertures for the 25 reception of screws and these ears have integral projecting tapering anchoring lugs 44 designed to be embedded in the door frame or casing and located at opposite sides of and spaced from a central ear or extension 30 45.

The front wall of the casing 40 is provided with an integral tongue 46 which is extended through a slot or opening 47 in the attaching member or side plate and the latter is also provided with a locking tongue or member 46 formed by partially severing a portion of the side wall or attaching member and adapted to be flexed from its normal position to permit the ready attachment of 40 the tongue 46 and arranged when returned to its normal position for holding the tongue 48 of the front wall in engagement with the side plate or attaching member.

The buffers while being assigned particularly for use in connection with automobile doors, are adapted to be advantageously employed on, and are applicable to, all door frames of any make.

What is claimed is:

50 1. The combination with a buffer having cushioning means, and designed to be secured to a door frame, of an approximately U-shaped buffer engaging spring designed to be mounted on a door and arranged to receive and engage the buffer for holding the door against longitudinal movement.

2. The combination with a buffer having cushioning means, and designed to be secured to a door frame, of an approximately 55 U-shaped buffer engaging spring arranged to receive and engage the buffer and an attaching strip extending across the intermediate portion of the spring and projecting therefrom and provided with terminal 60 attaching means.

3. A buffer of the class described including a casing provided at the inner portion with attaching means and having projecting lugs arranged to be embedded in a door frame for retaining the buffer in position 70 and for relieving attaching screws of shearing strain.

4. A buffer of the class described including a casing provided at the inner portion with an attaching flange or ear and having 75 projecting lugs located at opposite sides of the attaching flange or ear.

5. A buffer of the class described including a casing constructed of sheet metal angularly bent and provided at one of the terminal portions with spaced projections and having a tongue or extension at another terminal portion extending between the projections and interlocked with the same. 80

6. A buffer of the class described including a casing constructed of sheet metal angularly bent and provided at one of the terminal portions with spaced projections and having a tongue or extension at another terminal portion extending between the lugs, 90 said projections and tongue or extension being provided with coacting interlocking notches.

7. A buffer of the class described including a casing constructed of sheet metal angularly bent and provided at one of the terminal portions with spaced projections and having a tongue or extension at another terminal portion extending between the projections, said projections and tongue or extension being provided with coacting interlocking notches, and the tongue being of greater width than the space between the lugs and flexible to permit transverse bowing for engaging it with the lugs. 95

8. A buffer of the class described including a casing constructed of a single piece of sheet metal angularly bent to form four vertical walls and top and bottom horizontal walls, the sheet metal being split at the side edges of the top and bottom walls and the latter being provided with integral attaching ears, said casing being also provided at the vertical walls with terminal portions, one of the terminal portions having spaced projections and the other terminal portion having a tongue or extension passing between the projections. 100

9. A buffer of the class described including a casing constructed of a single piece of sheet metal angularly bent to form four vertical walls and top and bottom horizontal walls, the sheet metal being split at the side edges of the top and bottom walls and the latter being provided with integral attaching ears having anchoring lugs, said casing being also provided at the vertical walls with terminal portions, one of the terminal portions having spaced projections and the other terminal portion having a tongue or 115 120 125 130

extension passing between the projections, said lugs and tongue or extension being provided with coacting interlocking notches.

10. A buffer of the class described including a casing provided with projecting attaching ears having anchoring lugs projecting at right angles from the ears and arranged to be embedded in the material to which the buffer is secured.

10 11. A buffer of the class described includ-

ing a casing provided with a central projecting ear and having top and bottom projecting ears, the latter being provided with projecting anchoring lugs arranged at right angles to the top and bottom ears at the 15 edges adjacent the central ear.

In testimony whereof I have hereunto set my hand.

JAMES C. OLLARD.
